HOSE PULL

Carl E. Carlson, Fort Wayne, Ind., assignor to
 S. F. Bowser & Company, Inc., Fort Wayne,
 Ind., a corporation of Indiana

Application March 1, 1933, Serial No. 659,148

5 Claims. (Cl. 220—95)

My invention relates in general to fluid dispensing apparatus and has more particular reference to the type having a delivery pipe or hose adapted to be shifted from a normal inoperative position into various positions in order to dispense the fluid.

The invention contemplates specifically a dispensing device in which the fluid is delivered through a controllable device into a flexible delivery hose terminating in a delivery nozzle controlled by a manually operable valve. The controllable device may be a valve through which the fluid is forced under pressure from a remote storage or may be a pump. In any event, it is desirable to deliver the fluid to the hose under pressure shortly before the nozzle valve is opened to accomplish the delivery of the fluid to the customer. It is not desirable to apply the full operating pressure to the flexible delivery hose when idle.

An important object therefore is to provide a dispensing device including a flexible dispensing hose having a dispensing nozzle, adapted to be hung on a suitable support when not in use, and normally inactive mechanism for controlling delivery of fluid to the hose, including means whereby the fluid delivering mechanism may be actuated by the natural movements of the flexible hose in being arranged in position to deliver the fluid and whereby the mechanism may be secured against accidental actuation by the hose as long as the nozzle remains in idle position on its support.

Another important object of the invention is to utilize the movement of the hose or delivery pipe to actuate means controlling the flow of fluid to the delivery pipe and to provide additional locking means operative in such a fashion that the control means is necessarily locked before the delivery pipe can assume the inoperative position after a dispensing operation is completed, and remains locked until released by the removal of the delivery pipe out of the inoperative position as a preliminary to the making of a delivery.

Another object is to provide means to utilize the movement of the hose or delivery pipe to actuate means controlling the flow of fluid to the delivery pipe and to provide additional locking means operative in such a fashion that the control means is necessarily locked before the delivery pipe can assume the inoperative position after a dispensing operation is completed, and wherein the control means remains locked until

manually released after the delivery pipe has been removed from inoperative position.

Another object is to provide a device in which the hose must be moved from inoperative position before the dispensing device may be unlocked and conditioned for operation and wherein the hose thereafter must again be shifted to set the device in operation.

Numerous other objects and advantages of the invention will be apparent from the following description, which, taken in connection with the accompanying drawings, discloses a preferred embodiment of the invention.

Referring to the drawings:

Figure 1 is a partial perspective view of a dispensing device embodying my present invention;

Figure 2 is a horizontal section taken substantially along the line 2—2 in Figure 1;

Figures 3 and 4 are sectional views substantially along the line 3—3 in Figure 2;

Figures 5 and 6 are views taken respectively and substantially along the lines 5—5 and 6—6 in Figure 3.

To illustrate my invention, I have shown on the drawings a dispensing unit comprising a frame forming a casing 11 on and in which are mounted the several elements of the dispensing apparatus of my present invention. The casing is preferably formed with the conventional dial having pointers 15 for indicating the quantity of fluid dispensed, it being understood that the casing may contain a suitable meter 17 and fluid flow controlling device, such as a pump 19, whereby fluid to be dispensed may be delivered from a suitable storage (not shown) as by means of a conduit 21 through the control device 19 and the meter 17, which is operatively connected for actuating the pointers 15. From the meter, the fluid may be delivered through a "see" gauge 23 into the delivery pipe 25, which, in the illustrated embodiment, comprises a flexible hose, the outer end of which is provided with a discharge nozzle 27.

The discharge nozzle 27 is preferably provided with a valve for controlling the flow of fluid therethrough and has a guard 29 for a handle 31, which may be manually operated to control the valve, the valve being normally biased toward closed position and being compressible by means of the handle when it is desired to dispense fluid through the nozzle. The nozzle also has preferably a flexible delivery tube 33 connected to the discharge side of the valve. The casing carries a hook 35 stationarily mounted thereon in a con-

venient position and the hook has a pair of prongs 37 between which the hose may extend and which provide support for the nozzle when not in use. Suitable means may also be provided for interlocking the nozzle on the hook in such a fashion that accidental movement thereof from inoperative position may be prevented.

The casing also has a receptacle 39 for the reception of the discharge tube 33 when the nozzle 10 is supported on the hook, the receptacle comprising a casing having an opening exposed to the exterior of the housing 11 and being provided with a lug 42 by which the receptacle may be secured as on a frame member 51 of the housing.

15   The operation of the fluid control means 19 is
16   accomplished by movements of the hose 25 at the
17   will of the attendant in arranging the hose in po-
18   sition to accomplish delivery of the fluid being
19   dispensed. The hose, near its upper end, is at-
20   tached to a shaft 41, which is mounted for rock-
21   ing movement within a guard 43 carried by the
22   housing. The inner end of the rocking member
23   41 is connected to one end of a link 45, the other
24   end of which is attached to a lever 47. The lever
25   47 is pivoted on a bracket 49, which, in turn, is
26   secured to a member 51 forming a part of the
27   frame of the casing. The lever 47 also is pivotally
28   connected with the upper end of a bar 53, the
29   lower end of which is arranged to actuate the
30   fluid control device 19.

The fluid control device, as heretofore mentioned, may be a valve forming a part of the delivery line 21, but may be a fluid forcing device such as a pump, as shown in the drawings. In either event, the shaft 53 may be connected to actuate the device 19 either directly or indirectly. I prefer, however, to connect the shaft 53 so as to operate a switch 55, which in turn controls an electrical circuit 57 adapted to energize a motor 59, which is connected to the pump 19 for driving the same when the switch 55 is closed. Of course, any suitable arrangement may be employed for permitting the movement of the bar 41 initiated by movements of the hose 25 under the direction 40 of the attendant to control the operation of the device 19. It will be understood that movements of the hose 25 will cause the shaft 41 to tilt upon the casing and will draw the link 45 outwardly and cause the lever 47 to move in the direction 45 of the indicating arrow in Figure 3 of the drawings to the position shown in Figure 4. Such a tilting movement will draw the shaft 53 upwardly against the urge of a spring 61, which is connected between the shaft 53 and the frame member 51 of the housing to normally urge the parts to a position in which the pump is inoperative. By drawing the shaft 53 upwardly against the spring means 61, the switch 55 may be closed to complete the circuit 57 and set the motor 59 in 50 operation to drive the pump and thus force the fluid through the conduit 21, the meter 17, the "see" gauge 23 and the delivery hose 25 to be thence discharged through the nozzle 27 under the direct manual control of the attendant.

65 It is normally undesirable to have the discharge pressure applied to the hose while the apparatus is idle, that is to say, not discharging fluid through the nozzle 21. The hose 25, being of flexible material to facilitate its arrangement
70 in any convenient fluid delivery position, is naturally of somewhat weaker construction than is the solid conduit 21 through which the fluid is delivered under pressure to the hose and if the full discharging pressure is applied to the hose,
75 even when it is inoperative, its life may be con-

siderably reduced. I desire, therefore, to provide a means for ensuring that fluid will not be forced into the hose under pressure accidentally at such times when the delivery nozzle is hung in inoperative position on the hook 35. It should be understood, of course, that as soon as the delivery operation is terminated by the closure of the nozzle valve, the attendant will release the hose which will naturally gravitate to a position in which the shaft 41 is not tilted with respect to the housing and that this will result in the opening of the switch. However, movements accidentally imparted to the housing may operate the mechanism to close the switch even after the hose nozzle is hung upon its hook and in order to obviate this possibility, I provide a tiltable lever 65 mounted on the frame and extending outwardly through an opening 67. The lever is preferably tiltingly mounted in a bracket 66, which, in turn, has an arm 68 secured to the frame member 51. The lever has a cam portion 69 extending within the housing and adapted to bear against a portion 71 of the rod 53 and thus lock the rod against upward movement when the lever 65 is in the position shown in Figure 3 of the drawings. The portion of the lever 65, which projects out of the casing, is formed as a substantial plate 73 and the lever itself is located adjacent the hook 35 in such a position that the lever 65 is forced to assume the locking position before the nozzle can be hung on its supporting hook and the nozzle itself is formed so that the guard 29 cooperates with the plate 73 to retain the lever in locking position as long as the nozzle is supported on the hook.

After the nozzle is removed from the hook, the plate 13 of the lever may be grasped by the operator and drawn down to the position shown in Figure 4, the hook 35, being formed with a portion 75 providing a stop for limiting the downward movement of the lever. When in the lowered position, the plate 13 occupies the space above the hook and prevents the replacement of the nozzle thereon without raising the lever 65 to the locking position. When in the lowered position also, the cam portion 69 of the lever releases the bar 53 so that the same can be shifted in response to the movement of the hose under the control of the attendant in order to actuate the fluid flow controlling device 19 as heretofore described. 40 45 50

It is thought that the invention and numerous of its attendant advantages will be understood from the foregoing description and it is obvious that numerous changes may be made in the form, construction, and arrangement of the several parts without departing from the spirit or scope of my invention or sacrificing any of its attendant advantages, the form herein described being a preferred embodiment for the purpose of illustrating my invention.

Having thus described my invention, what I claim as new and desire to secure by Letters Patent is as follows:

1. Dispensing apparatus including a discharge conduit terminating in a nozzle, support means for the nozzle when not in use, delivery means to supply a fluid under pressure to the discharge conduit, control means for said delivery means, a shiftable lever having a portion adapted to be shifted to a predetermined locking position when the nozzle is mounted on the support and be held by the nozzle in a locking position, and means cooperatively associated with the lever for latching the control means against operation when the shiftable lever is so held in locking position by the 75

nozzle, said lever being shiftable into the space normally occupied by the nozzle when on the support in order to release the control means for operation after the nozzle has been removed from its support.

5 2. Dispensing apparatus including a discharge conduit terminating in a nozzle, support means for the nozzle when not in use, delivery means to supply a fluid under pressure to the discharge conduit, control means for said delivery means, a 10 shiftable lever having a portion adapted to be obstructed by the nozzle when the nozzle is mounted on the support and being held by the nozzle in a locking position, and means cooperatively associated with the lever for latching the 15 control means against operation when the shiftable lever is so held in locking position by the nozzle, said lever being shiftable into the space normally occupied by the nozzle when on the support in order to release the control means for operation 20 after the nozzle has been removed from its support, and means operatively associated with the discharge conduit for actuating the control means in response to movement of the discharge conduit after the nozzle has been removed 25 from the support.

3. Dispensing apparatus including a flexible hose terminating in a nozzle, support means for the nozzle when not in use, delivery means to supply a fluid under pressure to the flexible hose, 30 control means for said delivery means, a shiftable lever having a portion adapted to be obstructed by the nozzle when the same is mounted on the support and being held by the nozzle in a locking position, means cooperatively associated with the 35 lever for latching the control means against op-

eration when the shiftable lever is so held in locking position by the nozzle, said lever being shiftable into the space normally occupied by the nozzle when on the support in order to release the control means for operation after the nozzle has been removed from its support, and means operatively associated with the flexible hose for actuating the control means in response to movement of the flexible hose after the nozzle has been removed from the support.

4. Dispensing apparatus including a flexible hose terminating in a nozzle, support means for the nozzle when not in use, delivery means to supply a fluid under pressure to the flexible hose, control means for said delivery means, a shiftable lever having a portion adapted to engage the nozzle when the same is mounted on the support and be held by the nozzle in a locking position, and means cooperatively associated with the lever for latching the control means against operation 20 when the shiftable member is so held in locking position by the nozzle.

5. Dispensing apparatus including a discharge conduit terminating in a nozzle, support means for the nozzle when not in use, delivery means to supply a fluid under pressure to the discharge conduit, control means for said delivery means, a shiftable lever having a portion adapted to engage the nozzle when the same is mounted on the support and be held by the nozzle in a locking 30 position, and means cooperatively associated with the lever for latching the control means against operation when the shiftable member is so held in locking position by the nozzle.

35
CARL E. CARLSON.
